SEWING MACHINE

Hans Hacklander, Tinley Park, and Harold J. Le Vesconte, Western Springs, Ill., assignors to Union Special Machine Company, Chicago, Ill., a corporation of Illinois

Application September 19, 1936, Serial No. 101,588

5 Claims. (Cl. 112—63)

This invention relates to sewing machines; and it has reference more particularly to sewing machines of the "feed-off-the-arm" type exemplified in U. S. Patent No. 1,741,095, granted to Norman V. Christensen and Harold J. Le Vesconte on December 24, 1929, for seaming, among other things, tubular portions of garments. In the use of such machines, the fabric is rounded into the form of a tube upwardly about a fixed work supporting arm, and progressed along said arm, with edge margins thereof abutted or overlapped, to stitching mechanism for seaming.

The aim of our invention is to render a machine of the type specifically referred to, capable of performing all operations necessary to the production of a covered seam according to the method defined in U. S. Patent No. 2,079,569, granted to the aforesaid Norman V. Christensen on May 4, 1937, in which edge margins of the fabric are abutted in upstanding relation, trimmed to an even height, then laterally folded over flat into superimposition upon the fabric, and finally united by stitching including a central line of stitches through all three fabric thicknesses at the fold, and by outer parallel lines of stitches through the fabric at opposite sides of the fold, with crosswise connecting loops of looper thread overlying said fold.

The foregoing objective we realize in part, as hereinafter more fully explained, by providing mechanism for actuating the seaming needles as a group to penetrate the fabric from beneath, and by providing a looper or a group of loopers, to cooperate with the needles above the fabric.

In connection with stitching and looping mechanism having the above attributes, we further provide, also as more fully set forth hereinafter, coordinated mechanism above the work supporting arm of the machine for guiding the upstanding abutting margins of the fabric; trimming said margins; and folding them preparatory to seaming. The operator of our machine can thus at all times observe the performance of these several functions, and make any corrections that may be required to insure a uniform seam. This is a decided advantage over sewing machines of the Christensen and Le Vesconte type, supra, where in the looping and trimming is effected inside the tubularized fabric so that the tube had to be turned wrong side to enable removal of the trimmings and inspection of the seam and thereafter again turned right side out with attendant loss of time in the performance of these two turning operations.

Through provision, in addition to the features

already mentioned, of coordinated feed means adapted to advance the work outward of the work supporting arm of the machine, we are able to operate upon one section of fabric after another without stopping the machine, thereby eliminating a serious drawback common to sewing machines wherein each piece is advanced upward of the work supporting arm and has to be removed before another can be seamed.

Other objects and attendant advantages will appear from the detailed description which follows of the attached drawings, whereof Fig. I is a plan view of the machine with a portion of its frame base broken away and with protective covers removed to expose parts within a hollow of its frame.

Fig. II is a view partly in front elevation and partly in vertical section taken as indicated by the arrows II—II in Fig. I.

Fig. III is a view partly in elevation and partly in section, of the upper portion of the machine taken as indicated by the arrows III—III in Fig. I.

Fig. IV is a fragmentary view of the machine, partly in end elevation and partly in section taken as indicated by the arrows IV—IV in Fig. I, showing in part the mechanism for operating the loopers and the trimmer.

Fig. V is an end elevation of the machine taken as indicated by the arrows V—V in Figs. I and II.

Figs. VI and VII are plan sectional views taken as indicated respectively by the arrows VI—VI and VII—VII in Fig. V, and showing further details of the looping and severing mechanism.

Fig. VIII is a view partly in plan and partly in section taken as indicated by the arrows VIII—VIII in Fig. II showing the work supporting arm with covers removed to expose parts at the interior thereof.

Fig. IX is a fragmentary detail elevation looking as indicated by the arrows IX—IX in Fig. VIII.

Fig. X is a fragmentary view showing the front end of the work supporting arm in plan.

Figs. XI and XII are plan views respectively of the main and differential feed dogs of the machine.

Figs. XIII, XIV and XV are detail sectional views taken as indicated respectively by the arrows XIII—XIII, XIV—XIV and XV—XV in Figs. II and VIII.

Fig. XVI is a somewhat laterally exaggerated perspective view showing a part of the feed mechanism of the machine.

Fig. XVII is a fragmentary plan view of the

presser foot of the machine with certain appendages removed.

Figs. XVIII, XIX, XX, XXI are detail sectional views taken as indicated respectively by the arrows XVIII—XVIII, XIX—XIX, XX—XX and XXI—XXI in Fig. XVII showing sequential steps in the trimming and overlaying of the abutted ends of the edge portions of the fabric which are to be united.

10 Fig. XXII is a plan view of a supplemental presser plate associated with the presser foot and the needles of the machine.

Figs. XXIII and XXIV are diagrammatic sectional views showing the character of seam resulting from the needle arrangement illustrated in Fig. XXII.

Figs. XXV, XXVI and XXVII are views like Figs. XXII, XXIII and XXIV showing an alternative arrangement of the supplemental presser plate and the needles, and the seam resulting therefrom.

Figs. XXVIII and XXIX are views corresponding to Figs. XXII and XXIII showing another alternative arrangement of the supplemental presser plate and needles, and the seam resulting therefrom.

The frame 1 of our improved sewing machine corresponds substantially to that of Patent No. 1,741,095 hereinbefore referred to, and as shown, 30 has an elevated tubular longitudinal portion or sleeve 2 integral with a receding flat-bottomed base portion or bracket 3 which is adapted to be bolted to the top of a table or other support. At the left hand end (Figs. I and II), the sleeve 35 2 of the frame has a hollow forward-projection 4 whereto a hollow head 5 is suitably secured, and at the right hand end, said sleeve has a pendant neck 6. A work support in the form of a hollow arm 7 (Figs. I, II and VIII) extends 40 forwardly at an acute angle beneath the sleeve 2 of the frame 1, with its free left hand end overhung by the head 5. At its right hand end the work supporting arm 2 terminates in an upwardly-projecting neck 8 which abuts the pendant neck 45 6 of the frame 1. Screws 9 (Fig. II) passing through meeting internal lugs 10 and 11 of the neck portions 6 and 8 serve to secure the work support 7 rigidly to the frame 1. The feed, stitching and trimming mechanisms which are 50 hereinafter described under separate headings, all derive motion from a horizontal main shaft 12 which is journaled in spaced bearings 13, 14, 15 and 16 within the hollow of the longitudinal sleeve 2 of the frame 1, said shaft extending to 55 the exterior at the left hand end of the machine as shown in Figs. I and III where it is provided with a pulley 17 for coordination, by a belt, with a suitable source of power of any usual character, not shown. Removable covers 18, 19 and 20 respectively closing openings 21, 22 and 23 in 60 the top of the sleeve 2 and the head 5, afford access to the main shaft 12 and the parts connected therewith.

65 Feeding mechanism

This mechanism comprises a main feed dog 25, and a differential feed dog 26 (Figs. II, and VIII—XII) respectively having toothed faces which project up through openings in the throat plate 27 at the forward end of the work supporting arm 7 to react against the presser foot 28 of the machine in progressively advancing the fabric being seamed in the direction indicated by the arrows in Figs. I and II, outward of said arm. 70 The feed dogs 25, 26 are respectively formed with

square section shanks 29, 30 (Figs. VIII, XI and XII) which bear against wear plates 31, 32 respectively at opposite sides of the arm 7, and which are secured by screws to the forward ends of tubular feed bars 33, 34 extending longitudinally of the hollow of said arm. As shown in Figs. VIII and XIII the feed bars 33 and 34 are slidingly engaged about midway of their lengths, in a rocker 35 fulcrumed on the eccentric center portion 36 of a pin 37 extending transversely of 10 the work-supporting arm 7. By rotatively adjusting the fulcrum pin 37, it is possible to shift the orbit of movement of the two feed dogs 25 and 26 vertically, the adjustment being fixable by a set screw 38. To the right hand end of the 15 main feed rod 33 is secured a clevised collar 39 (Figs. VIII and XVI) with an upward lug affording a pivotal connection 40 for the lower end of a lengthwise-adjustable connecting rod 41 which extends upward through the communicating holes 20 of the necks 6 and 8, and which is connected at its upper end to an eccentric 42 on the main shaft 12, see Figs. I and III. Thus, during each rotation of the main shaft 12, the rods 33 and 34 carrying the feed dogs 25 and 26 will be 25 moved up and down about the transverse pin 37 as an axis since both said rods are engaged in the rocker 35 as previously explained. By adjusting the length of the eccentric rod 41 in connection with the regulation afforded by the fulcrum pin 37, it is possible to vary the angle of 30 the major axis of the path of travel of the feed dogs or to adjust their path of travel bodily, vertically or both. As the feed rods 33 and 34 are rocked in the manner just explained, they 35 are shifted back and forth longitudinally by means including another vertical pitman 43, which, at the top is connected to a crank 44 at the right hand end of the main drive shaft 12, and at the bottom, to a stud 45 midway of the 40 length of the horizontal arm 46 of a bell crank lever 47 fulcrumed on a fixed transverse pin 48 within the hollow of the work supporting arm 7. As shown in Figs. II and XVI, the bell crank lever 47 has a pendant arm 49 connected by a horizontal link 50 with the clevised collar 39 at the 45 right hand end of the main feed rod 33. Accordingly, through this arrangement, a fixed longitudinal movement is imparted to the main feed dog rod 33. At its outer end, the horizontal arm 50 46 of the bell crank lever 47 is coupled, by means of a drop link 51, with a horizontal link 52 whereof the left hand end, is pivotally connected to a block 53 fixed upon the right hand end of the differential feed bar 34, said block being apertured 55 for sliding guidance on the main feed rod 33. The pivot 54 connecting the links 51 and 52 is suspended by a lazy bar 55 from the end of an angularly-adjustable arm 56 whereof the axis stud 57 has bearing in the frontal side of the 60 work supporting arm 7. Secured by a screw 58 to the projecting end of the stud 57 is an adjustable disk 59 having a finger projection 60 and carrying a pair of opposing circumferentially adjustable stops 61 (Fig. IX) to cooperate with a 65 headed pin 62 which extends through an aperture in the side of the arm 7 and through a registering arcuate slot 63 in said disk. A spring 64 in compression between a nut 65 at the inner end of the stop pin 62 and the side wall of the 70 arm 7, maintains the disk 59 in frictional engagement with the outer face of said arm 7 to prevent it from shifting accidentally. As the bell crank 47 oscillates about the pin 48, the pivotal connection 54 will be raised and lowered and 75

the vertical movement thereof translated into horizontal movement of the differential feed bar 34 by action of the lazy bar 55 as the latter swings back and forth about its connection with the end of the supporting arm 56. With the disk 59 adjusted as shown in Fig. IX, a minimum throw is imparted to the differential feed bar 34, but by turning the disk in the direction of the arrow to move the arm 56 from the dotted position to the dot and dash line position, the throw of the differential feed bar may be increased, such throw being always proportional to that of the main feed bar 33 since both of said bars are actuated from the bell crank lever 41. As a consequence of the described arrangement, the action of the differential feed bar may be altered as desired while the machine is running.

The feeding mechanism, per se, forms the subject matter of a separate application, Serial No. 101,589 concurrently filed herewith.

Needle mechanism

This mechanism includes an arm 66 (Figs. II and V) which is fulcrumed on a transverse pin 67 within the work supporting arm 7 at the outer end thereof, said arm carrying three transversely-spaced needles 68, 69 and 70 which are curved concentrically with the swinging axis 67 and which move upward through elongate apertures in the throat plate 27. Swinging movement is imparted to the needles 6 through a horizontal link 71 within the hollow of the work support 7 beneath the feed rods 33, 34. At its right hand end the link 71 is pivotally connected to the pendant arm 72 of a bell crank lever 13 which is free to swing on the fixed pin 48 hereinbefore referred to, and which has a substantially horizontal arm 75 coupled, by means of a third vertical pitman 76, with a crank 77 on the main shaft 12 immediately adjacent the crank 44, see Figs. II, III, VIII and XIV. Accordingly, during each rotation of the main shaft 12 the needles 68-70 are concurrently swung up to penetrate the fabric from beneath.

Looper mechanism

As shown in Figs. II and V, the machine is provided with a pair of loopers 78 and 79 to cooperate respectively with the needles 68 and 69, 70, said loopers being secured in a pendant looper arm 80 fulcrumed for swinging movement crosswise of the direction of feed about a stud 81 projecting laterally from the horizontal arm 82 of a bell crank lever 83, (see Figs. II, V and VI) said bell crank lever being integrally formed with a rock shaft 84 journaled in a depending bearing lug 85 of the head 5. The loopers 78, 79 it will be observed from Fig. V, are curved concentrically with the fulcrum stud 81 and swung back and forth in performing loop taking and shedding movements as a consequence of the action of a vertical pitman 86, which, at its lower end, is connected to a lateral arm 87 of the looper carrier 80. At its upper end the pitman 86 is connected by a ball joint to a crank 88 on a counter-shaft 89 journaled in bearings 90 and 91 within the hollows of the lateral frame projection 4 and the attached head 5. As shown in Figs. I and IV, the countershaft 89 is driven in unison with the main shaft 12 through a pair of intermeshing miter gears 92, 93. The arm 82 of the bell crank lever 83 above mentioned is connected by another pitman 94 (Figs. I, III, V and VI) with an eccentric 95 on the counter shaft 89 so that needle clearing movements are imparted to the loopers 78, 79 through oscillations of the shaft 84 with

the loopers passing from the front to the rear of the needles as required during each loop forming cycle.

Presser mechanism

The presser foot of the machine indicated at 28 in Figs. II, VII, and XVII-XXI is flat and formed with an upstanding arched shank 96 which is secured by a screw 97 to the lower end of a presser bar 98. As shown, the presser bar 98 passes through a sleeve 99 journaled in the bottom of the head 5 and an aligned guide bushing 100 in the top of said head. The presser bar 98 is yieldingly urged downward by a heavy helical spring 101 in compression between a collar 102 on said bar and the bushing 100, which latter is threaded into the head 5 and formed at the top with a knurled head 103 so that it may be adjusted to vary the pressure of said spring. A lock nut 104 serves to secure the bushing 100 in adjusted positions. The presser bar 98 is held against rotation through engagement of a clevised lateral projection 105 of the presser foot shank 96 with a guide stud 106 depending from the head 5. The presser foot 28 is longitudinally divided with provision of a passageway 107 Fig. VII for the edge margins M, M' of the fabric F. A supplemental presser plate 108 with a longitudinally notched clearance opening for the needles 68-70 occupies the rear portion of the guideway 107 and has a connection with said presser foot at 109. A spring 110 (Figs. II, V and VII) bears upon the supplemental presser plate 108 and thus yieldingly urges it downward to effectively flatten the fold N of the seam and so holds it as it is presented to the needles.

As shown in Figs. XVII, XIX and XX one side edge of the guideway 107 at the entrant end thereof is formed with a bevel 111 of which the angle gradually flattens and with which cooperates a correspondingly beveled edge 112 of a folding element 113 to gradually turn the upstanding abutting margins M, M' of the fabric over laterally before they reach the supplemental presser plate 108. From Figs. VII and XVII it will be observed that the folding element 113 is slidable in a transverse slot 114 in the top of the presser foot and urged inward by a spring 115. In order that variations in the edge thickness of the fabric may be compensated for, the presser foot 28 is provided at opposite sides of the passage 107 with flat underlying spring shoes 116 whereof the ends 117 and 118 are turned up and over the toe and heel ends of said foot. To enable lifting of the presser foot in starting the fabric beneath it, there is provided a control means including a "Bowden" wire 120 (Figs. I and IV) which is secured at one end to the collar 102 on the presser bar 98, and passes upward and rearward through an angularly fixed guide tube 121 within the contiguous hollows of the frame 1 and the head 5. The other end of the wire 120 is secured to one arm of a bell crank lever 122 fulcrumed at 123 on a fixed bracket 124 at the exterior of the frame 1, the other arm of said bell crank lever 122 being connected by means of a chain 125 with a foot treadle or knee lever, not illustrated.

The presser foot, per se, forms the subject matter of a separate application, Serial No. 102,400 concurrently filed herewith.

Trimming mechanism

Clamped to the projecting end of the sleeve 99 at the bottom of the head 5 is a downwardly reaching arm 126 (Figs. II, V and VII) in the

end of which is secured a flexible arcuate trimming blade 127 having its center of curvature in the axis of said sleeve. The sharpened end of the trimming blade 127 shears against the 5 sharpened end of an opposing ledger blade 128 which overhangs the passage 107 in the presser foot and which is held in a transverse slot of said presser foot by a clamp plate 129. An end tongue extension 130 of the moving blade 127 10 bears upon the top of the fixed blade 128 and thereby insures the maintenance of the cutting edges in proper shearing alignment vertically. Oscillatory movement is imparted to the sleeve 99 and in turn to the trimming blade 127 carried 15 by it, through connection of a ball arm 131 at the top of said sleeve within the head 5 by a short link 132 with the upright arm 133 of the bell crank lever 83 hereinbefore described in connection with the looper mechanism.

20

Threading

En route from supply packages, not shown, the threads for the loopers 78, 79 pass to tensioning devices 135, 136 (Figs. I and IV) mounted upon 25 a longitudinal supporting bar 137 on the frame 1, then through suitable guides (not shown) to a rotary take-up 138 forming part of a hand wheel 139 at the outer end of the counter shaft 89, and finally to the loopers. As shown, the rotary 30 take up 138 comprises a pair of disks 140, 141 which are spaced relative to each other and the back of the hand wheel 139 to afford spaces for the respective looper threads, and are connected by an eccentrically disposed loop engaging stud 35 142. Through location of the rotary take-up 138 on the head 5 over the outer end of the work supporting arm 7 in close proximity over the loopers 78, 79, positive and effective control is had of the looper threads. The threads for the 40 three needles 68—70 similarly pass through other tensioning devices 143, 144 and 145 on the bar 137, and from thence pass through suitable thread guides along the arm 7 to the needles 68—70.

The operation of the machine is as follows: 45 The fabric F is rounded upwardly about the rear end of the work arm 7 into the form of a tube and edge margins M, M' thereof brought into contiguous upstanding relation as shown in Fig. XIII. With the fabric so placed, it is directed beneath 50 the presser foot 28, care being taken that the upstanding edge margins M, M' properly enter the longitudinal passage 107 of said presser foot. Upon starting the machine, the fabric F is progressively advanced forwardly along the arm 7 by action of the feed dogs 25 and 26. Incident to 55 advance of the fabric, the upstanding margins M, M' are trimmed by the opposing trimming blades 127 and 128, the abutting edge margins progressively laid laterally in superimposition 60 flat upon the fabric by action of the folding element 113, and finally stitched and looped by the needles 68—70 and the loopers 78, 79. In consequence of the described construction, arrangement and actuation of the trimming, folding and 65 sewing instrumentalities, their functioning can be clearly observed by the operator. Under these circumstances it is possible to predetermine uniform trimming with assurance of a straight and neat covered seam. Since the cutting is effected 70 above the fabric, the trimmings are immediately disposed of and it is therefore only necessary to turn the tube right side out to complete the operation. This is a decided advantage over the patented machine hereinbefore referred to in 75 connection with which the tube had to be turned

wrong side out to remove the trimmings or to inspect the seam and afterwards turn the tube again to bring its right side out. By feeding off the arm 7, successive fabrics can be serially operated upon without stopping the machine with 5 consequent attainment of an increased output from the machine. The gang grouping of the needles and the loopers not only favors structural simplicity, but permits operation of the 10 machine at high speeds.

With the needles arranged as in Figs. II, VII and XXII, that is to say, with the needles 69 and 70 abreast but in advance of the central needle 68 in the direction of feeding, the crosswise connecting looper loop L' of a pair of outer 15 needle loops S' and S² formed during one stitching cycle as in Fig. XXIII, is covered by the looper loop L of a central needle loop S during the succeeding stitching cycle.

By placing the central needle in advance of the 20 needles 69 and 70 as shown in Fig. XXV, the looper loop L of a central needle loop S formed as in Fig. XXVI during one stitching cycle, is covered by the crosswise looper loop L' of a pair of outer needle loops S', S² formed in the next knitting 25 cycle as shown in Fig. XXVII.

By arranging all three needles 68, 69 and 70 abreast and employing a single looper 78 as in Fig. XXVIII, the needle loops S, S¹ and S², S³ may be connected by a looper loop L during each 30 stitching cycle after the manner shown in Fig. 35 XXIX.

It is to be particularly noted that in all cases the central needle loops S pass through the fabric F as well as the two superimposed margins M, M' at the fold N, and that the fold is covered by the crosswise looper loops L' connecting the outer lines of needle loops S¹, S² which pass through the fabric immediately beyond the fold.

From the foregoing it will be seen that we have 40 provided a simple and efficient machine which can be operated to form a seam which is advantageous in that on one face of the garment no covering thread is required to conceal raw fabric edges, the seam thus having an attractive 45 appearance as compared with ordinary seams.

While we have described our improved machine as being particularly useful in the production of tubular articles, it is not necessarily 50 limited to this field since it can be adapted as well in uniting separate fabric sections. It is also to be understood that our machine can be used in the formation of seams other than those illustrated in Figs. XXIII, XXVI and XXIX without departing from the spirit of our invention as defined in certain of the appended claims, by employing a single needle with a single cooperating looper, or two needles abreast with a single cooperating looper, or two needles in staggered relation and a looper to cooperate with each needle to form parallel rows of stitches. Moreover, by suitable modification of the stitch forming mechanism, our improved sewing machine can be 55 adapted to form other stitching including the 60 form shown in the Christensen Patent No. 1,822,799, dated September 8, 1931.

Having thus described our invention, we claim:

1. In a sewing machine, a work support; feeding means for longitudinally advancing fabric 70 tubularized about the work support, with its lateral edges abutted in upstanding relation; means beneath the work support for actuating the feeding means; means for laterally folding over the abutted margins downwardly flat into superim- 75

position upon the exposed face of the fabric; a group of upwardly-penetrating needles transversely-arranged with respect to the direction of feeding, certain of said needles being adapted to 5 pass through the three thicknesses of fabric at the fold, and others through the single fabric thicknesses at opposite sides of the fold; a common holder for the needles; means beneath the work support for actuating the holder; looper 10 means adapted to cooperate with the needles above the work support; and means for actuating the looper means.

2. In a sewing machine, a work support; feeding means for longitudinally advancing fabric tubularized about the work support, with its lateral edges abutted in upstanding relation; means beneath the work support for actuating the feeding means; means for laterally folding over the abutted margins downwardly flat into superimposition upon the exposed face of the fabric; a group of upwardly-penetrating needles, certain of said needles being adapted to pass through the three thicknesses of fabric at the fold, and others being offset with respect to the first subdivision 20 in the direction of feeding and adapted to pass through the single fabric thicknesses at opposite sides of the fold; a common holder for the needles; means beneath the work support for actuating the needle holder; a pair of loopers 25 adapted to cooperate respectively with the two subdivisions of the needles above the work support; a common holder for the loopers; and means for actuating the loopers.

3. In a sewing machine, a work support; feeding means for longitudinally advancing fabric tubularized about the work support, with its lateral edges abutted in upstanding relation; means beneath the work support for actuating the feeding means; means above the work support for trimming the abutted margins; actuating means above the work support for the trimming means; means operative after the trimming to laterally fold over the abutted margins downwardly flat into superimposition upon the exposed face of the fabric; a group of upwardly-penetrating needles transversely arranged with respect to the direction of feeding, certain of said needles being adapted to pass through the three thicknesses of fabric at the fold and others 40 through the single fabric thicknesses at opposite sides of the fold; a common holder for the needles; means beneath the work support for actuating the holder; looper means adapted to 45 cooperate with the needles above the work support; and means for actuating the looper means.

4. In a sewing machine, a horizontal work support; feeding means for longitudinally advancing fabric tubularized about the work support, with its lateral edges abutting in upstanding relation; an elevated horizontal arm with a lateral 50 extension at its free end overreaching the corre-

sponding end of the work support; a rotary drive shaft journaled longitudinally of the arm; a transverse rotary shaft journaled on the lateral extension of the arm and driven from the longitudinal shaft; a vertical presser bar confined to 5 axial movement by the lateral extension of the arm; a presser foot carried by the presser bar, said presser foot providing means for initially guiding the upstanding margins of the fabric and for afterwards folding said margins downwardly flat into superimposition upon the exposed face of the fabric; a trimming blade horizontally oscillatable about the presser bar and adapted to trim the upstanding margins of the fabric before the folding; a needle adapted to 10 upwardly penetrate the three thicknesses of fabric at the fold; means beneath the work support for actuating the needle; a looper pivotally mounted above the work support to cooperate with the needle; means deriving motion from the transverse shaft aforesaid for actuating the trimming blade and the looper; and mechanism beneath the work support deriving motion from the longitudinal drive shaft for actuating the feeding means and the needle.

5. In a sewing machine, a horizontal work support; feeding means for longitudinally advancing fabric tubularized about the work support, with its lateral edges abutting in upstanding relation; an elevated horizontal arm with a lateral extension at its free end overreaching the corresponding end of the work support; a rotary drive shaft journaled longitudinally of the arm; a transverse rotary shaft journaled on the lateral extension of the arm and driven from the longitudinal shaft; a vertical presser bar confined to 30 axial movement in the lateral extension of the arm; a presser foot carried by the presser bar, said presser foot providing means for initially guiding the upstanding margins of the fabric and for afterwards folding said margins downwardly flat into superimposition upon the exposed face of the fabric; a trimming blade horizontally oscillatable about the presser bar and adapted to trim the upstanding margins of the fabric before the folding; a group of needles transversely arranged with respect to the direction of feeding, certain of said needles being adapted to upwardly penetrate the three thicknesses of fabric at the fold and others adapted to upwardly penetrate 35 the single fabric thicknesses respectively at opposite sides of the fold; loopers pivotally mounted above the work support and adapted to cooperate with the needles; means deriving motion from the transverse shaft aforesaid for actuating the trimming blade and the loopers; and mechanism beneath the work support deriving motion from the longitudinal drive shaft for actuating the feeding means and the needles.
